UNITED STATES PATENT OFFICE.

JOHN A. BRILL, OF PHILADELPHIA, PENNSYLVANIA.

DESIGN FOR A SIDE FRAME FOR CAR-TRUCKS.

SPECIFICATION forming part of Design No. 26,406, dated December 15, 1896.

Application filed November 3, 1896. Serial No. 610,988. Term of patent 14 years.

To all whom it may concern:

Be it known that I, JOHN A. BRILL, a citizen of the United States, and a resident of Philadelphia, in the county of Philadelphia and State of Pennsylvania, have invented and produced a new and original Design for a Side Frame for Car-Trucks, of which the following is a specification.

My invention relates to a new and original design for a side frame for a car-truck; and it consists in the shape or configuration of the same, substantially as hereinafter described, and shown in the accompanying drawings, forming part of this specification, in which—

Figure 1 is a plan view; Fig. 2, a side elevation; Fig. 3, an end elevation, and Fig. 4 a sectional elevation on the line *a b*, Fig. 2.

The side frame is substantially rectangular and comprises the following elements, having the disposition or configuration substantially as herein shown and described.

At 1 are inverted-U-shaped yokes having the inner and outer arms 2 and 3, the arms 3 being connected at the top and bottom by bars 4 and 5 and both bars centrally by the parallel upright bars 6 and 7, and extending

between the angles formed by the intersection of the arms 3 of the yoke and the lower bar 5 on the one hand and the bars 6 7 and top bar 4 on the other are diagonal chords 8. 30 A rib 9 projects from the outer arms 2 of the yokes and the top of bar 4. On the lower bar 5, between the bars 6 7 and extending outwardly on each side, is a flat bed-plate 10, and extending between the under surface of 35 the plate 10 to the lower bar 5 are bracket-webs 11.

Under the arch of the yokes 1 are circular caps 12, and extending outwardly from the bars 6 7 and in the plane of the bars 4 5 are 40 lugs.

Having described my invention, I claim—

The design for a side frame for car-trucks, substantially as herein shown and described.

Signed at New York, in the county of New 45 York and State of New York, this 17th day of October, A. D. 1896.

JOHN A. BRILL.
